UNITED STATES PATENT OFFICE.

JOHN HOWARTH, OF SALEM, MASSACHUSETTS.

IMPROVEMENT IN APPARATUS FOR DISTILLING OFF GASES AND VAPORS.

Specification forming part of Letters Patent No. 42,772, dated May 17, 1864.

To all whom it may concern:

Be it known that I, JOHN HOWARTH, of Salem, in the county of Essex and State of Massachusetts, have invented certain new and useful Improvements in Apparatus for Making Gases, &c.; and I do hereby declare that the following description, taken in connection with the accompanying drawings, hereinafter referred to, forms a full and exact specification of the same, wherein I have set forth the nature and principles of my said improvements whereby my invention may be distinguished from all others of a similar class, together with such parts as I claim and desire to have secured to me by Letters Patent.

When coals, shales, woods, &c., are placed within retorts that are heated only externally to a temperature necessary to expel the volatile products from these substances, dry destructive distillation takes place and the said volatile products are changed and their quality is impaired. This process is, in fact, a baking or roasting one.

The present invention relates to a process of distilling coals and other carbonaceous materials in which both internal and external heat are applied to the retorts, the internal heat being furnished by passing superheated steam through the material to be acted upon, and the external heat by a suitable arrangement of flues, combustion-chamber, &c.

I have practically demonstrated after many experiments that the best results are obtained by causing the superheated steam to perform the actual work of extracting the volatile products from coal, wood, &c., and keeping the temperature of the external heat only sufficiently high to prevent radiation, by this means avoiding the evils of destructive distillation and producing products in larger quantities of much greater commercial value than by any process heretofore used.

The object of the present invention is to so construct an apparatus for the production of oils, gases, &c., from carbonaceous materials as to cause the internal heat afforded by the superheated steam always to exceed in temperature that of the external heat, and in such a manner that the process in this respect shall be a self-regulating one, so that dry destructive distillation cannot possibly take place. I have also constructed a new form of an up-

right retort which is particularly applicable to the working of the above-named process.

The figures of the accompanying plate of drawings represent my improvements. Figure 1 is a longitudinal vertical section. Fig. 2 is a transverse vertical section; Fig. 3, a horizontal section; Fig. 4, a plan or top view; and Fig. 5, a detail view of superheaters, showing the mode of construction.

a a in the accompanying drawings represent a brick furnace; *b b*, fire-pot; *c c*, grate; *d d'*, two superheaters, the peculiarity of which in their construction and arrangement will be hereinafter explained, placed side by side and resting on the fire-tile floor *e*, covering the flues through which the heat, smoke, and other products of combustion from the fire-chamber pass on their way to the outlet-flue *f*, leading to the chimney. The arrangement of these flues and the direction in which the heat, smoke, &c., pass are as follows, reference being had to arrows in the drawings, viz: *g g' g'* are openings in side walls of fire-pot *b*; *h h'*, two central flues extending from fire-chamber the entire length of the furnace, into which the said openings *g g' g'* open; *i i'*, two outside flues connecting with flues *h h'* at the rear end thereof and extending the entire length of the furnace to the front wall thereof, where apertures *j j'* connect the same with the chamber *k*, above the superheaters, the outlet from which is at *f*, as before stated. The products of combustion, &c., passing from the fire-chamber, first enter the central flues, then the outside flues, and finally the chamber *k*, where they diffuse themselves and then pass out into the descending flue.

To the superheater *d* steam is admitted at *l*, and, passing into and through its various compartments *m m m*, &c., then enters at *n* the other superheater, *d'*, from whence, after having passed entirely through the same, as in *d*, is conducted through the pipe *o* to the vertical retorts *p* and *q*, placed over and resting upon the rear superheater, *d'*, in the chamber *k*. In the case of the retort *p*, the steam coming from the superheaters, as described, enters at the bottom thereof, through connecting-pipe *r*, and in the other, *q*, at the top thereof through connecting-pipe *s*. The retort *q* is divided into compartments *t* and *u* by a partition-plate, *v*, extending nearly to the bottom of the retort,

but leaving an opening, *w*, for communication between the two, into the smaller one, *u*, of which the superheated steam is admitted, as described.

x' are pipes respectively leading from the top of the retorts *p* and *q* to the tar-main *y*, containing water, &c., and, entering the same, extend nearly to the bottom, for a purpose to be hereinafter specified.

z is a pipe entering the smaller compartment, *u*, of retort *q*, through which liquid hydrocarbons are fed into the same, a suitable cock being used to regulate the amount thereof at pleasure.

Having thus described the arrangement of the devices composing my apparatus, I will now proceed to describe the manner in which the same is operated either to form hydrogen alone or hydrocarbon gaseous vapors, or to produce oil in conjunction therewith.

For the production of only hydrogen gas, the retort *q* is used, the larger compartment of which I charge with wood, wood-charcoal, spent tan, coke, peat, or any other dry carbonaceous material, while into the smaller one the superheated steam is admitted.

For the production of hydrocarbon gases, the liquid hydrocarbon is fed in through pipe *z* in small quantities, and, mingling with the superheated steam, becomes vaporized, and the superheated steam and vapors thus formed then pass together into and up through the dry carbonaceous material in the larger compartment heated to a red heat. Thus the superheated steam is decomposed into its elementary gases—hydrogen and oxygen—the oxygen of which is absorbed by the fixed carbon within larger the compartment, *t*, which leaves the hydrogen to unite with the volatile hydrocarbon, thereby giving the hydrogen its due quantity of carbon and make it into a rich illuminating-gas. The gas then passes through the exit-pipe *x'* into the tar-main *y*, in the usual manner; but for the production of both oil and gas and other products the retort *p* is used, the operation of which, after having been first charged with coal, shales, wood, &c., is as follows: The superheated steam passes into the retort at the bottom, diffusing itself through the mass therein while ascending, thus evap-

orating the volatile products from the same, which rapidly pass out through the exit-pipe *x*, before referred to, with the steam into the tar-main *y*, as in the usual manner.

The peculiar construction of the super-heaters described and used in my new apparatus consists in dividing them into several chambers by means of partition-plates *b'b'*, &c., communicating with each other, the purpose of which is to retard the passage of steam through the same, in order that it may be heated to a greater and sufficient degree of heat before reaching the retorts. These superheaters can be also cast in one piece, which is a great advantage, apertures *c'c'*, &c., which are afterward closed with cast-iron plugs, being made at opposite ends of each chamber for removing the sand-core from the same.

It will be observed by the foregoing description that from the relative position of the superheaters, flues, and retorts the most intense heat from the furnace is necessarily absorbed by the superheaters, while the lesser and remaining heat passes around the retorts, thus insuring that the internal temperature of the retorts shall always exceed that of the external heat, so that the work of expelling the volatile products will be effected wholly by the superheated steam, the external heat being only sufficient to prevent radiation.

Having thus described my improvements, I shall state my claims as follows:

1. So combining devices for superheating steam, flues for the passage of products of combustion, and a suitable retort or retorts containing carbonaceous materials as to cause the internal heat, or that produced by the superheated steam, to always predominate over the external heat and perform the work of extracting the liquid and volatile products from the retort or retorts without producing destructive distillation, substantially as described.

2. The double-chambered upright retort, arranged and operating substantially as described, and for the purpose specified.

JOHN HOWARTH.
